UNITED STATES PATENT OFFICE

91,402

DESIGN FOR A BOWL OR SIMILAR ARTICLE

William W. Dodge, Jr., Asheville, N. C.

Application January 18, 1932. Serial No. 42,522

Term of patent 14 years

To all whom it may concern:

Be it known that I, WILLIAM W. DODGE, JR., a citizen of the United States of America, residing at Asheville, in the county of Buncombe and State of North Carolina, have invented a new, original, and ornamental Design for a Bowl or Similar Article, of which the following is a specification, reference being had to the accompanying drawing forming a part hereof.

The single figure of the drawing is a plan or face view of a shallow bowl with upwardly and outwardly curving or flaring walls, and here shown of circular form. Produced in or upon this face are numerous substantially radial ribs or

elevations and depressions, more or less irregular, which, owing to the high reflecting power of the polished silver used, cause deep or dark shadows in the depressions, intensifying the apparent brightness of the raised portions. Viewed across the bowl, its far side closely resembles running or rippling water, or a cascade, constantly changing in response to movement of bodies in proximity to the ornamented surface. The contour of the bowl or similar article may vary.

I claim:

The ornamental design for a bowl or similar article, as shown and described.

WILLIAM W. DODGE, JR.
